LOUNGE CHAIR

Franklin Richardson, Glendale, Calif.

Application February 19, 1954, Serial No. 29,113

Term of patent 14 years

(Cl. D15—11)

FIG. 2.

FIG. 1.

FIG. 4.

To all whom it may concern:

Be it known, that I, Franklin Richardson, a citizen of the United States, residing at Glendale, in the county of Los Angeles, State of California, have invented a new, original, and ornamental Design for a Lounge Chair, of which the following is a specification, reference being had to the accompanying drawing, forming a part hereof.

Fig. 1 is a view in side elevation of the lounge chair embodying my new design, the chair being shown in its upright position;

Fig. 2 is a view in front elevation of the same;

Fig. 3 is a rear view in elevation of the same; and

Fig. 4 is a view in side elevation of the same, the chair being shown in its reclining position.

I claim:
The ornamental design for a lounge chair, as shown.
